UNITED STATES PATENT OFFICE.

OLIVE R. BURLINGAME, OF BOSTON, MASSACHUSETTS.

FOOT-REST FOR PIANO-STOOLS.

SPECIFICATION forming part of Letters Patent No. 280,907, dated July 10, 1883.

Application filed June 15, 1882. (No model.)

To all whom it may concern:

Be it known that I, OLIVE R. BURLINGAME, a citizen of the United States, residing in the city of Boston, county of Suffolk, and State of Massachusetts, have invented certain new and useful Improvements in Foot-Rests for Piano-Stools, of which the following is a specification.

It will be understood that the ordinary piano-stool in common use is designed for a full-sized person of adult age, as a small child seated upon such a stool has nothing to rest its feet upon, and thus steady the body while practicing upon the piano. The effort to sit securely upon the oval top of the stool causes an unnatural strain upon nearly every part of the body, especially the spinal column. It is very fatiguing, and often a serious injury to children not naturally strong. Furthermore, if the child is not firmly seated, it cannot have that perfect control of the hands and arms required for piano practice. Therefore the object of this invention is to combine a foot-rest with the ordinary piano-stool, upon which rest the feet of the child may be placed, and by which the body may be held as steadily and easily as if the feet were placed upon the floor. I accomplish this purpose by the mechanical device illustrated in the accompanying drawings, in which—

Figure 1 is a sectional elevation taken on the dotted line A to B in Fig. 3. Fig. 2 is an end section of this device, taken on the line C to D in Figs. 1 and 3, enlarged to the full size. Fig. 3 is a sectional view of Fig. 1, taken on the dotted line E to F in Fig. 1. Fig. 4 is a sectional view, showing the manner of adjusting the device beneath the seat of the piano-stool, enlarged to full size. Fig. 5 is a developed plan of the stirrup, and Fig. 6 is a side view of the same. Figs. 5 and 6 are enlarged, but not to the full size.

In Fig. 1, *a* represents a simple form of a grooved angle-iron which is easily inserted in the socket, as shown in Fig. 4.

The bolt *b* is firmly secured in the grooved angle-iron *a*, and passes through the slotted slide or extension-piece *c*, and an ordinary thumb-nut, *d*, (either with or without a washer, 50 as the case may require,) is placed thereon.

The slide or extension-piece *c* is slotted, as shown in Fig. 3, so as to span the bolt *b*. The sides are beveled to fit the groove in the angle-iron *a*, as shown in the end section in Fig. 2, but is made a trifle larger than the groove in 55 which it slides, so that an open space will be left, as shown at *e* in Fig. 2. By this means the two pieces are easily and firmly held together by the bolt *b* and thumb-nut *d*, and no side or lateral motion is possible.

At the bottom of the piece *c* the cross-bar *f* (best shown in Fig. 3) furnishes the means of adjusting the stirrups *g g*, and to which the same said stirrups are bolted, as shown in Fig. 3, which shows a section of the instep of the 65 stirrup. Fig. 5 shows a developed plan, and Fig. 6 a side view, of the stirrup. These stirrups may be forged, or cast in suitable metal, as may prove the most desirable. In Fig. 6 it will be observed that the back part is formed 70 to fit the heel of the shoe, the back being turned upward at *h* to prevent slipping backward, while the side pieces, *i*, at the instep *g* prevent the foot from slipping off at the side.

The bracket *k* in Fig. 4 (represented with 75 the broken section of a piano-stool, *l*,) is in the usual form used for similar purposes, and is readily understood without further description.

Having thus described my invention, what I 80 claim as new, and desire to secure by Letters Patent, is—

1. The combination of the piano-stool *l* with the angle-iron *a*, extension-bar *c*, stirrups *g g*, bolt *b*, and nut *d*, made, arranged, and operating substantially as and for the purpose described.

2. A foot-rest for a piano-stool, composed of the angle-iron *a*, extension-bar *c*, stirrups *g g*, adjusting-screw *b*, and thumb-nut *d*, made and 90 arranged substantially as set forth.

3. The combination of the stirrups *g g*, having guides *h* and *i*, all formed substantially as shown, with the bar *c* and angle-iron *a*, made and adjusted substantially as specified.

OLIVE R. BURLINGAME.
